UNITED STATES PATENT OFFICE.

BROR E. WESTLIN, OF ARLINGTON, NEW JERSEY, ASSIGNOR TO OTIS ELEVATOR COMPANY, OF JERSEY CITY, NEW JERSEY, A CORPORATION OF NEW JERSEY.

DOOR-LOCK.

1,132,755.

Specification of Letters Patent. Patented Mar. 23, 1915.

Application filed October 25, 1907. Serial No. 399,100.

To all whom it may concern:

Be it known that I, BROR E. WESTLIN, a citizen of the United States, residing at Arlington, in the county of Hudson and State of New Jersey, have invented a new and useful Improvement in Door-Locks, of which the following is a specification.

My invention relates to door locks especially adapted for use in connection with 10 electrically controlled elevators.

One of the objects of the invention is to provide an improved construction which shall operate as a safety device to prevent the circuit controlled by the lock from being 15 closed before the door is locked, even when the parts become worn or are out of proper alignment by reason of the door sagging or warping, or for other reasons.

Another object of the invention is to provide a universal door lock of the above character adapted for use with the various forms 20 of doors used in connection with elevators, and adapted to the varying conditions found in elevator practice.

Other objects will appear more fully hereinafter, and the novel combinations of elements will be pointed out in the appended 25 claims.

Referring to the drawings, Figure 1 is a 30 plan view of the door lock applied to a swinging door and showing the door and jamb in section; Fig. 2 is an elevation of the same; Fig. 3 is a view similar to Fig. 2 showing the lock turned upside down or end 35 for end and certain parts reversed to suit this position; Fig. 4 is a plan view of the door lock applied to a sliding door; Fig. 5 is an elevation thereof; and Fig. 6 is a view similar to Fig. 5, showing the lock in a reverse position, Figs. 5 and 6 corresponding 40 to Figs. 3 and 2, respectively.

Referring to Figs. 1 and 2, the door lock 45 casing comprises a body portion 1 and a lock plate 2 which carries the lock mechanism, and which is secured to the door jamb 3. The swinging door 4 carries a catch 5 secured in position by the plate 6. The door jamb is formed with a rabbet 29 to receive the edge of the door and form a 50 stop for the door when closed. A latch 7 is pivoted on a stud 8 on the plate 2, and is removably secured by a cotter pin 9. Pivoted to the latch 7 is a depending rod 10, the lower portion of which is reduced in diam-

eter and forms a stem 11. On this stem 55 is mounted a sleeve 12 of fiber or other insulating material, held against sliding movement on the stem by friction or otherwise. Above the sleeve 12 is a metal contact strip or plate 13 slidingly mounted on the stem 11 and yieldingly held against the sleeve 12 by a coil spring 14. The contact strip 13 is adapted to bridge two metal contact plates 15 and 16 when the rod 10 is lowered. These contact plates are mounted 65 on a plate 17 of insulating material secured to the casing by screws 18. Mounted in the plate 16 and another contact-carrying plate 19 are a pair of contact rods 20 which extend through a flange 21 formed on the insulating plate 17, and project beyond the side of the casing. These contact rods are yieldingly held in their outward position by coil springs 22, and are adapted to be bridged by a metal contact strip 23, carried 70 by but insulated from the catch plate 6 on the door. Binding screws 24, 25 on the contact plates 15 and 19, respectively, form means for connecting the wires of the controlling circuit which is completed between 75 80 said binding screws when the contact strips 13 and 23 bridge their respective contacts.

Journalized in a bearing lug 25' and extending laterally from the lock case is a rock-shaft 26. A crank arm 27 is removably 85 secured to the rock shaft by a screw-bolt 28, and carries at its outer end a cam-engaging roller 30. A pin 31 carried by the rock-shaft 26 near its inner end is adapted to engage a pin 32 extending laterally from 90 the rod 10, and lift the latch 7 when the shaft is rocked. The movement of the rock-shaft in the opposite direction is limited by the pin 31 engaging a stop 31'.

The latch 7 is of rather peculiar construction, being formed with two downwardly extending noses or projections *a* and *b* with a recess 33 between them and a recess 34 behind the nose *b*. The catch 5 is adapted to enter the recess 33 when the door is in the 95 position shown in Figs. 1 and 2 and lock it against being opened. In this position the contacts 20 are separated from the contact strip 23, and the contact strip 13 is held up out of contact with the plates 15, 16. If the 100 door is swung in to its fully closed position, the nose *b* rides over and engages behind the catch 5. In this position the bridging con-

tact strips 13 and 23 are both in engagement with their contacts and a circuit is closed between the binding screws 24, 25. The peculiar form of latch 7 as above described forms an important feature of my invention, as will appear presently.

The rock-shaft 26 is operated by means of a cam on the elevator car coming in contact with the roller 30 and swinging the arm 27 whenever the car is brought to rest in a position opposite the door to which the lock is attached. When the shaft is rocked the pin 31 lifts the rod 10 and with it the latch 7, and unlocks the door. The operation of the rock-shaft by means of a cam on the elevator car being a feature well known to those skilled in the art, and forming no part of the present invention, it is not deemed necessary to illustrate it in this case. It has also been thought unnecessary to show the controlling circuit which is opened and closed by the door lock, as this is not a part of applicant's invention.

In operation, if the door is not fully closed, the parts will assume the position shown in Fig. 2 in which the controlling circuit is open and the car cannot be moved until the door is completely closed. No special advantage obtains from the use of this double-nosed latch so long as the various parts remain properly adjusted and unworn. If, however, the door should sag, or the latch should be filed or become worn, or the parts otherwise out of their relative position so that the contact strip 13 is lowered to contacting position before the door is fully closed, the circuit will still remain open at the contact strip 23 until after the nose *a* has reached its locking position, so that the door will be locked before the controlling circuit can be closed to start the car. But if the recess 33 were not provided and the parts should become worn or out of alignment so as to prematurely close the contact 13, then the contacts 20 which engage the contact 23 before the latch is closed, would complete the circuit and permit the car to be started before the door was locked. If the nose *a* were omitted entirely, the result would be the same when the parts were out of adjustment as with the recess 33 omitted. Also, with the nose *a* omitted, if the door should become warped or the relative position of the parts otherwise changed to bring the contacts 20 and 23 nearer together, the circuit might be closed through said contacts before the latch 7 was lifted to open the circuit at contact 13, and therefore again permit the operation of the car before the door was locked. The nose *b* could not be omitted, as it is necessary to hold the contacts 20 against the strip 23 and retain the controller circuit closed and permit the operation of the car. It will thus be seen that the peculiar construction

of the latch insures the locking of the door before the car is operated, while at the same time permitting a wide range of variation in the relative positions of the parts.

Fig. 3 shows the lock adapted for use with a door swinging shut from the right instead of from the left as viewed in Fig. 1. The same lock is used as in Figs. 1 and 2, but with the arrangement of parts changed as follows:—The entire lock is reversed or turned end for end, the latch 7 is reversed on its pivot 8, so that the noses *a*, *b* project downwardly, pin 31 on the rock-shaft is positioned on the opposite side of the pin 32, the crank arm 27 is reversed on its shaft so as to extend upwardly, the contact strip 13 is placed at the outer end of the insulating sleeve 12, the stop 31' is removed and a ring or washer 14' is placed on the stem 11 as a stop for the spring 14. The plate 6 is also turned end for end and the position of the catch 5 relative to the plate 6 is reversed. The operation is the same as in Fig. 2.

Figs. 4 and 5 show the lock applied to a sliding door 4'. The lock case 1 is here attached to a bracket 40 on the door jamb. The catch plate 6 is also attached to a bracket 41 on the door. The lock mechanism itself is arranged as in Fig. 3, except that the rock-shaft 26' extends in a direction at right angles to that of Fig. 3 in order that its crank arm 27 and roller 30 may be properly positioned in the elevator shaft.

Fig. 6 shows the lock applied to a sliding door closing from the left instead of from the right as in Figs. 4 and 5. Fig. 6 bears the same relation to Fig. 5 that Fig. 2 does to Fig. 3.

From the foregoing description taken in connection with the drawings it will be apparent that the door lock is adapted, with a few changes in the arrangement of parts, to both sliding and swinging doors, and doors opening either to the right or to the left. These changes are readily made when the lock case is open. Another valuable feature of the present invention is that when the case is open all the parts are exposed to view so that repairs can readily be made.

I do not wish to be limited to the exact constructions shown, as various changes in details of construction and arrangement of parts might be made without departing from the spirit and scope of the invention.

What I claim as new and desire to secure by Letters Patent of the United States is:—

1. In a door lock, the combination of electrical contacts carried by the door and jamb and movable into engagement when the door is closed, mechanism for locking the door against opening before said contacts are brought into engagement, and means comprising an additional contact device in

circuit with said electrical contacts and operated by said mechanism for controlling an electric circuit through said contacts.

2. In a door lock, the combination with 5 electrical contacts on the door and jamb positioned to be engaged when the door is almost closed, of mechanism for locking the door against opening movement before it reaches position to engage said contacts, and 10 operative also to lock the door when fully closed, and means operated by said mechanism to control an electric circuit through said electrical contacts.

3. In a door lock, the combination with 15 electrical contacts on the door and jamb in position to be brought into engagement as the door approaches its closed position, of mechanism for locking the door against opening movement before the contacts are 20 engaged, and operative also to lock the door in its fully closed position, and means operated by said mechanism to control a circuit through said contacts.

4. In a door lock, the combination with 25 contacts on the jamb and door in position to be engaged as the door approaches its closed position, of a catch, a latch formed with two noses adapted to engage the catch and lock the door against opening movement before and after the contacts have been 30 brought into engagement, and means operatively connected to said latch to control an electric circuit.

5. In a door lock, the combination with 35 a catch on the door, of a pivoted latch supported by the door jamb and formed with two projections positioned to engage the catch respectively before and after the door is fully closed, and electrical contacts carried by the door and latch, respectively, and 40 movable into engagement only after the door is fully closed.

6. In a door lock, the combination of a 45 device for locking the door against being opened when it has reached a nearly but not fully closed position, and an electrical switch operated by said device only when the door is fully closed.

7. In a door lock, the combination with means for locking the door closed, of a 50 switch operated by said means, and a second switch comprising co-acting contacts carried by the door and door jamb and arranged in circuit with the first named switch and operated by the door independently of the 55 door locking means.

8. In a door lock, the combination with means for locking the door, of a switch operated by said means, and a second switch operative independently of said first switch 60 and controlling the same circuit as said first named switch and comprising contacts on the door jamb and door, respectively.

9. In a door lock, the combination with mechanism for locking the door against being opened after it reaches a nearly closed position and also locking it in its fully closed position, of a switch connected to 65 said mechanism and closed thereby as the door is locked in its closed position, and a second switch in series with the first and having contacts on the door jamb and door, respectively, in position to be connected after said mechanism has operated.

10. In a door lock, the combination with 75 a case attached to the door jamb, of a latch pivoted in the case and extending laterally therefrom, a rod pivoted to the latch, a contact carried thereby, a stationary contact in position to be engaged by the contact on 80 the rod when the latch is lowered, and a catch on the door, said latch being formed with two notches, one to receive the catch when the door is nearly closed and lock the door against opening movement but with 85 said contacts separated, and the other notch to receive the catch when the door is fully closed, and also permit engagement of said contacts.

In testimony whereof, I have signed my 90 name to this specification in the presence of two subscribing witnesses.

BROR E. WESTLIN.
